CLAIM

The ornamental design for an axle repair kit, as shown and described.

DESCRIPTION

FIG. 1 is a perspective view of an axle repair kit showing my new design;

FIG. 2 is a perspective view of one of the arms thereof separated from the center circular unit;

FIG. 3 is a front view of one of the arms thereof;

FIG. 4 is a side view of one of the arms thereof;

FIG. 5 is a top view of one of the arms thereof;

FIG. 6 is a perspective view of the center circular unit of the kit;

FIG. 7 is a front elevational view of the center circular unit of the kit;

FIG. 8 is a back view of the center circular unit of the kit; and,

FIG. 9 is a side view of the center circular unit of the kit. The broken line showing of internal threads is included for the purpose of illustrating environment and forms no part of the claimed design.
